UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

PAPER-FOLDING DEVICE

Application filed August 8, 1922, Serial No. 580,439. Renewed May 17, 1928.

This invention relates to the folding rolls of a machine for folding highly illustrated products at a high rate of speed.

The principal object of the invention is to provide a new method of folding and means connected with the folding rolls for positively forwarding the folded products without subjecting the printed, or especially the highly illustrated, surfaces to pressure between the rolls, and thus avoiding the smutting and smudging of the sheets by the offset of ink from one sheet to another. It is also an object of this invention to provide means for accomplishing the above mentioned result which will work at a very high rate of speed. Means is also provided for positively and effectively creasing the fold of the product.

Reference is to be had to the accompanying drawings, in which

Fig. 1 is a sectional view of a pair of folding rolls constructed in accordance with this invention and showing them in their proper position with relation to the folding cylinder;

Fig. 2 is an enlarged end view of these rolls showing them partly in section;

Fig. 3 is a side view of one of the rolls;

Fig. 4 is a view of the folding blade with slots for the folding pins to pass through;

Fig. 5 is a transverse sectional view showing modifications;

Fig. 6 is a view similar to Fig. 1 showing another modification, and

Fig. 7 is a side view of one of the rolls shown in Fig. 6.

The offsetting of ink from highly illustrated parts of newspapers and magazines between the folding rolls of the folding machine has been a serious problem since high speed presses have been in operation. This ink does not have time to dry before the web is cut up into sheets, or other folded products, and passed between the folding rolls. These rolls have usually pressed on the sheets throughout their areas in order to feed them forward accurately, and fold them with a good crease. This causes trouble in two ways. The folding rolls themselves take up ink from the outside of the sheet and put it back on the next sheet. Attempts have been made to obviate or lessen this difficulty by registering the folding roll-

ers so that they contact with the sheets at the same point always, and I wish to retain that feature in this machine. Also the illustrated or highly inked parts on the insides of the folding products come against each other and have heretofore been pressed into close contact, thus smearing the inside surfaces.

This invention is designed for the purpose of positively feeding the folded products between the folding rolls without exerting pressure at any point on their surfaces so that neither one of these difficulties is likely to occur. For this purpose the two folding cylinders 20 are set a little farther apart than usual, so that their solid surfaces will not come into pressing contact with the paper passing between them from the folding cylinder 19. They are provided, or one of them is, with rows of pins 21 extending around the circumference at both ends and adapted either to penetrate the paper along the margins or to contact with these margins sufficiently to cause the paper to move in exact unison with the rolls.

The pins 21 can be located directly on one or both the rolls as shown in Figs. 6 and 7, or they can be mounted on separate collars 22 as shown in Figs. 1, 2 and 3. These collars preferably are mounted to yield and have central passageways larger than the shafts or studs of the rolls that pass through them. This can be done by mounting two studs 24 on each end of the roll 20 and surrounding each stud by a rubber washer 25. The collars 22 are provided with two opposite perforations fitting said washers and are held in position by nuts and washers 26 of the ordinary type if desired. This permits the two collars which contact with each other at each end of the pair of rolls to yield slightly and enables the pair of rolls to take products of different thicknesses.

These pins will enter or impinge against the margins of the product so as to keep it in time with the rollers, and prevent its lagging in the folding operation. The feeding, therefore, is more positive than it has been heretofore.

The pins are firmly fixed either on the roller or the collar. However, in the form

shown in Figs. 6 and 7 these pins are set directly in the roller and are rigidly mounted. This, as shown in these two figures, provides a method of folding between the folding rolls without pressing any part of the product under pressure.

I have also shown the rolls in Figs. 1, 2 and 3 and also in Fig. 5 each provided with a longitudinal folding block 27. These blocks may have pins 28 mounted rigidly on them as shown in Fig. 5, those in one of the blocks alternating with those of the other. They can have the pins mounted on the roll as shown in Fig. 1 and the block slidable on them and forced outwardly by springs 29. Either one or both of the blocks may be spring mounted, and either or both can be provided with pins, as shown respectively in Figs. 2 and 5. In this case the folding blade 30 is provided with slots or notches 31 at its folding edge through which the pins sweep when they impale the product that is tucked between the rollers by the folding blade.

These folding blocks are provided when desired for the purpose of forming a crease at the fold of the product and getting positive pressure at that point along the margin that occurs there, but in Figs. 6 and 7 this feature is omitted and the folding is done entirely without pressing contact by the folding rolls with any part of the printed product.

It is found that the products will pass through these rolls in either case and be folded and fed positively and accurately without the transfer of the ink from one sheet to another by the pressure of the rolls because in all cases there is no pressure of the rolls on the printed surfaces.

Although I have illustrated and described only three forms of the invention I am aware of the fact that modifications can be made therein by any person skilled in the art without departing from the scope of the invention as expressed in the claims.

Therefore, I do not wish to be limited to all the details of construction herein shown and described, but what I do claim is:—

1. The combination of a pair of folding rolls for folding printed products located far enough apart to prevent contact by the rolls with the printed product, said rolls having projections spaced apart around their circumference for engaging the printed product at points on its margin and constantly and positively forwarding it between the rolls as they rotate without placing any part of the printed product in contact with the rolls and under pressure of said rolls.

2. As an article of manufacture, a folding roll having sharp points projecting from its surface for piercing the printed product to be folded and forwarding it, said points being located in restricted areas around the roll, and constituting the only means on the roll

for forwarding the printed product after the fold is made.

3. As an article of manufacture, a folding roll having at the end thereof a circumferential series of pins having sharp points 70 projecting radially from the roller for impinging on the product, and a longitudinal series of pins.

4. The combination with a pair of folding rolls for folding printed products having sharp pointed projections around their circumferences for impinging upon the printed product at points on its surface and forwarding it between the rolls as they rotate, one of said rolls having a series of pins arranged longitudinally thereon for engaging the folded product at the folded margin and positively feeding it.

5. In a folding machine, the combination with a folding cylinder and a pair of folding rolls, of a series of pins on said rolls for impinging upon and forwarding a doubled printed product between them, means for folding it without placing any part of the printed product under pressure of said rolls, said cylinder having a folding blade provided with slots registering with the pins to permit them to pass through them.

6. The combination with a folding cylinder and a pair of folding rolls therefor having means around their circumference for engaging the printed product at points at its margins and forwarding it between the rolls as they rotate, one of said rolls having a series of pins arranged longitudinally thereon for engaging the folded product at the folded margin and positively feeding it, and a folding blade on said cylinder provided with slots for the pins of said rolls to pass through.

7. The method of folding printed products which consists in passing them between a pair of rolls having their surfaces located far enough apart to leave a space between them wider than the thickness of a folded product and prevent the application of pressure, by said rolls, to any part of the printed product and piercing the product progressively to positively forward it with the rotation of the rolls by contact with the printed product at the margins thereof.

8. As an article of manufacture, a folding roll for receiving folded products from a folding cylinder and having fixed pins arranged in a series along the roll for engaging a folded product at the folded margin.

9. The combination of a pair of folding rolls, one of them having a longitudinal series of radial pins projecting into contact with the other roll.

In testimony whereof I have hereunto affixed my signature.

HENRY A. WISE WOOD.
